CHARLES H. TRUE, Inventor

By HIS Attorney *O.V. Thiele*

UNITED STATES PATENT OFFICE.

CHARLES HENDERSON TRUE, OF HAMMOND, INDIANA, ASSIGNOR TO THE SUPER-HEATER COMPANY, OF NEW YORK, N. Y., A CORPORATION OF DELAWARE.

DOUBLE-TUBE RETURN-BEND.

1,373,465.

Specification of Letters Patent.

Patented Apr. 5, 1921.

Application filed May 24, 1919. Serial No. 299,623.

To all whom it may concern:

Be it known that I, CHARLES H. TRUE, a citizen of the United States, and resident of Hammond, in the county of Lake and State of Indiana, have invented certain new and useful Improvements in Double-Tube Return-Bends, of which the following is a specification.

My invention concerns itself with pipe arrangements in which one set of pipe lies within another, the ends of each set of pipes being connected by return bends so that independent inner and outer conduits are formed. It has for its purpose the provision of an improved form of the return bends connecting the pipes and a novel mode of making them. The advantages of a return bend according to the present invention and of the proposed method of making it will appear clearly from the following description. This description is to be read in connection with the accompanying drawing. In the latter, Figures 1 and 2 show portions of two of the outer and two of the inner pipes connected, the one by an incomplete and the other by a substantially complete return bend; Fig. 3 illustrates the same two parts placed into the relative position which they are to occupy finally; Fig. 4 is a section on line 4—4 on Fig. 3; Fig. 5 shows the return bend after an additional step has been taken toward finishing it; Fig. 6 shows the completed double-pipe return bend; Fig. 7 is a longitudinal central section of Fig. 6 taken at right angles to it; Fig. 8 illustrates a modification; Fig. 9 is a section on line 9—9 of Fig. 8; Fig. 10 shows a further modification.

In making the constituent parts of my double-pipe return bend, I employ the method described fully in U. S. Patent 1,169,209 to myself and N. T. McKee as joint inventors. The complete return bend illustrated in Fig. 1 is made by the process described in that patent. The die employed in its manufacture is usually referred to as a breeches die on account of its shape and will be so referred to hereinafter. The return bend as shown in Fig. 1 will herein after be referred to as an incomplete return bend. By it, the two pipes 1 and 2 are joined, the material being portions of the pipes themselves. The structure is at this stage open at the end 3. It is assumed here-

in that the reader is familiar with the patent mentioned above and with this art in general and no detailed description of the process of making this incomplete return bend is believed necessary. The structure illustrated in Fig. 2 consists of the two pipes 4 and 5 joined at their ends by a return bend 6, which, it will be noticed, is closed at its end 7 and has projecting from it a relatively long nub 8. This return bend 6 is made by the same process as the one of Fig. 1 and is closed preferably by swaging machine as fully described in U. S. Patent 1,255,355 to myself and C. A. W. Brandt as joint inventors. The pipes 4 and 5 will be seen in Fig. 2 to have received a double bend or offset at the points 9 and 10. This is for the purpose of placing the axes of the pipes 4 and 5 the same distance apart as those of the pipes 1 and 2 of the structure of Fig. 1. It will be understood that the pipes 1, 2, 4 and 5 are of any desired length.

The two structures thus briefly described are placed one inside of the other as illustrated in Fig. 3. They are held in this relative position by any means desired. Thereafter the incomplete return bend of the outer structure is suitably heated and swaged down as at 11, in Fig. 5. By an additional step which is merely a continuation of the swaging just spoken of, this return bend is finally closed as shown in Fig. 6. It will be found to advantage in practice, during the step of drawing down the outer incomplete return bend to the shape of Fig. 5, to place the inner structure so that its crotch 12 will be in contact with the point 13 of the inner structure, and to hold the two in the relative position they are to occupy, only during the additional step of giving it the shape of Fig. 6. The nub 8 as well as the portion 11 are heated to a welding heat for this last step. In this manner, the wall 11 and the nub 8 become one integral structure and this connection serves to hold the inner return bend in fixed relation to the outer.

Under certain circumstances it may be undesirable to hold the two sets of pipes in this relatively fixed position. In such cases, I do not provide a nub 8 on the inner return bend (see Fig. 8) but rely on supports 14 for keeping the two properly spaced. This

permits of longitudinal relative movement, as will be evident.

In Fig. 10, I illustrate a variation in which the inner return bend instead of being closed and provided with a nub 8 is left open and is provided with a connecting cylindrical portion 15. The outer return bend is drawn down and connected to it as shown. This is of utility in certain places.

10 It will be manifest that numerous variations, not only in the method employed in producing my double-tube return bend, but also in the return bend itself will occur in practice.

15 What I claim is:

1. The process of making double-pipe return bends comprising the steps of connecting the ends of two pipes by an incomplete return bend, connecting the ends of two smaller pipes to form a complete return bend, inserting the latter into the former so that the two are substantially coaxial, and then finishing the incomplete bend.

2. The process of making double-pipe return bends comprising the steps of connecting the ends of two pipes by an incomplete return bend by the breeches die operation,

connecting two smaller pipes to form a complete return bend and spacing these pipe centers the same distance as those in the former pair of pipes, inserting the smaller pair into the larger, and finally finishing the incomplete bend.

3. The process of making double-pipe return bends comprising the steps of connecting the ends of two pipes by an incomplete return bend, connecting two smaller pipes to form a complete return bend, provided with a terminal projection, inserting the latter pair into the former and swaging down and closing the end of the incomplete return bend uniting it to the projection.

4. The process of making double-pipe return bends comprising the steps of connecting the ends of two pipes by an incomplete return bend, connecting the ends of two smaller pipes to form a complete return bend, inserting the latter into the former so that the two are substantially coaxial, providing means to keep the two relatively spaced and finally closing the incomplete return bend.

CHARLES HENDERSON TRUE.
